DESK LAMP

Robert J. Carrithers, Lincolnwood, Ill.

Application July 21, 1950, Serial No. 11,304

Term of patent 7 years

(Cl. D48—20)

To all whom it may concern:

Be it known that I, Robert J. Carrithers, a citizen of the United States and a resident of Lincolnwood, in the county of Cook and State of Illinois, have invented a new, original, and ornamental Design for a Desk Lamp, of which the following is a specification, reference being had to the accompanying drawing forming a part thereof, and in which:

Fig. 1 is a perspective view of a desk lamp showing my new design;

Fig. 2 is a bottom plan view of the same; and

Fig. 3 is a perspective view of the rear of the same.

I claim:

The ornamental design for a desk lamp, as shown.

ROBERT J. CARRITHERS.
